VENTILATORS

Leo Henneberger, 145 Division Ave., Massapequa, N.Y.
Filed Mar. 3, 1961, Ser. No. 93,051
5 Claims. (Cl. 98—37)

The present invention relates to ventilators.

Known types of ventilators commonly employed under extreme weather conditions are defective to the extent that they do not adequately provide against flooding or leakage of water through or around the ventilator in driving rain or sea and are not readily adjustable to accommodate weather changes. For some purposes, as for ventilating small craft, available devices are excessively costly, inflexible in use and involve undue trouble and expense in installation. Also, they are unnecessarily complex and difficult to maintain in working condition.

An object of the present invention has been to provide a directionally adjustable ventilating device of relatively few parts which can be made to advantage from rugged but relatively light weight material, such as butyrate, linear polyethylene or the like, and which is so constructed that it can be securely mounted in operative position on a boat deck, or the like, and yet be freely adjustable to maintain effective ventilation without flooding or water leakage under extreme wind, sea and rain conditions and regardless of wind or weather direction. It has also been an object of my invention to provide a ventilator of which the component parts can be made inexpensively of suitable plastic, can be readily assembled and can be securely mounted in any desired operative position with comparative ease. Other objects and beneficial aspects of this invention will be apparent from the description and the accompanying drawings.

An embodiment of my invention comprises in general a base and lower baffle member adapted to be mounted on a deck or the like and having a sleeve extending through a hole in said deck, a frame having a generally cylindrical outer wall portion and an inner wall portion coaxial therewith and spaced inwardly from and connected to the outer wall by a web interposed between said walls and provided with drain openings, said inner wall forming an air duct open at its inlet and outlet ends and said frame being rotatably mounted on and in telescoping connection with portions of said base. A housing having perforations extending through a lateral wall portion is mounted co-axially on and in position to substantially enclose the frame and is freely rotatable therewith to different angular positions of adjustment. A second or upper baffle is operatively mounted in the housing between said perforations in its wall and the air inlet end of the air duct of the frame and is accessible through the air outlet end of said air duct for hand manipulation to turn the housing and said frame about their common axis and the axis of said duct. Said component parts are advantageously made of butyrate, linear polyethylene, or material having equivalent physical properties.

An embodiment of my invention is illustrated in the drawings accompanying this specification and wherein:

FIGURE 1 is a front elevation of a ventilator, as mounted on a deck, or the like, shown in section;

FIGURE 2, a fragmentary top plan view, with parts broken away, showing portions of the frame and of the upper baffle member mounted thereon in effective water-deflecting position between said frame and perforations in the housing as seen in FIGURE 3;

FIGURE 3, a fragmentary view in approximately central vertical section on the line 3—3 of FIGURE 1;

FIGURE 4, a fragmentary view in vertical section on the line 4—4 of FIGURE 2, showing the position of laterally positioned depending legs of the baffle member in relation to the frame and in water deflecting relation to

2

perforations at the ends of the series of perforations in the transversely disposed wall portion of the housing, as seen in FIGURES 1 and 3;

FIGURE 5, a fragmentary view in vertical section on the line 5—5 of FIGURE 4;

FIGURE 6, a bottom plan view showing structural features of the base including a lower baffle in the form of a peripheral flange extending from a central sleeve;

FIGURE 7, a fragmentary view in vertical section on the line 7—7 of FIGURE 6, showing the base mounted on a deck, or the like, with its central sleeve extending through a hole therein; and

FIGURE 8 is a fragmentary view in vertical section on the line 8—8 of FIGURE 6 showing a bedding or sealing compound filler in the grooves formed between ribs of the base which, when mounted as in FIGURE 6, have their edges closely engaging portions of the deck surface surrounding the opening in the deck.

Referring to said drawings, an embodiment of my invention includes, as seen in FIG. 3, an integrally formed base bearing member or mounting plate A preferably of a suitable plastic such as polystyrene, butyrate or the like having a sleeve 10 which fits into a hole 11 in a deck or wall 12 and has a peripheral flange 13 which provides a lower baffle integral and coaxial with said sleeve and provided at its underside with radially spaced downwardly extending concentric ribs 14 and 15 between which are spaces or grooves for receiving a filler 16 of sealing or bedding compound or other suitable substance. Said flange is beveled at its peripheral edge 13a to more effectively deflect water which washes in along the deck under the outer edge or skirt of the ventilator housing. Base A is secured to a portion of deck 12 surrounding hole 11 by screws 17 applied through holes 18, FIGURE 6, in said flange 13. As seen in FIGURE 7, the upper end portions of the shanks of said screws pass through and are in effect sealed in the filler mass 16 when the base is mounted in place on deck 12. Also when the base is so mounted, ribs 14, 15 and the filler mass 16 between them press closely against the outer deck surface and thus prevent leakage of water from outside into the space between sleeve 10 and hole 11.

As seen in FIGS. 6 and 7, sleeve 10 is formed with a narrow annular beveled flange 19 projecting inwardly from its inner surface and with bosses extending inwardly in position to provide angularly spaced flat bearing faces 19a for a purpose to be described.

A ventilator according to the present invention also includes an integrally formed frame or spider indicated generally at B which provides a centrally positioned generally cylindrical air duct with an air inlet end 20 at the upper side of deck 12 and flange 13, as viewed in FIGURE 3, and an air outlet end 21 extending through said sleeve 10 and open at the underside of deck 12. Said outlet end 21 of said air duct engages and is freely rotatable on the bearing surfaces 19a of sleeve 10 to provide effective guiding and retaining means for the frame B with minimum friction between said air duct portion thereof and said sleeve 10.

Frame B includes a peripheral annular outer wall 22 radially spaced from said inner end 20 of the duct and also a depending annular rib 23 spaced outwardly from an intermediate portion of said duct and forming therewith, in effect, an annular groove, the under face of said rib 23 when the parts are assembled being adapted to ride on opposed portions of the upper face of flange 13. As seen in FIG. 3 said annular rib 23 overlaps or telescopes with the upper end 11a of sleeve 11 which fits into said annular groove to form a snug joint between said base A and frame B but permitting free turning of said frame in relation to the base. A web having angularly spaced radial arms 24 connects outer wall 22 to the inner end 20

of said duct and provides water discharging ports 25 between said arms and between said outer wall 22 and said rib 23. Said arms 24 are provided with longitudinally extending ribs 26 which serve both to strengthen the frame structure and to support a baffle in a manner to be described.

As seen in FIG. 3, arms 24 and thus ports 25 of frame B are spaced vertically above deflector flange 13 of the bearing A thus providing a guiding path for water discharging through said ports. And the peripheral portion of said flange 13 in addition to serving as a lower baffle against flooding from the deck is also positioned to facilitate the discharge of water outwardly or away from the joint between rib 23 and the opposed top surface of flange 13 and from around screws 17 toward said deck.

The frame or integral part B is preferably made of suitable flexible plastic, as polystyrene, butyrate or the like, provided with angularly spaced wedge-shaped lugs 27 extending radially outwardly from an outlet end portion of the air duct. Said lugs are so positioned and dimensioned that when the air duct is pushed downwardly through sleeve 19 and past the beveled face of flange 19 to the position shown in FIG. 3, the duct wall being sufficiently resilient will yield inwardly to allow the lugs to pass said beveled flange to and through the outlet end of the duct. Upon reaching end position, said lugs snap outwardly to interlock with said flange 19 and the lower edge of sleeve 10. Thus, said parts are retained against accidental disengagement while frame B remains free to rotate in relation to base A.

An upper baffle, as C, also of suitable plastic material includes a deflector plate 28 advantageously of domed cross-sectional contour, provided at its under or concave side with a finger-piece 29. Legs 30 extending downwardly from the peripheral edge of deflector 28 and integral therewith are notched at 31 to straddle the ridges of ribs 26 of frame B. Said ribs are provided with abutments 32 which are wider than said notches 31 and thus, when the parts are assembled, afford positive stops to retain said baffle with its deflector portion in substantially coaxial relation to the air duct and so that its outer peripheral edge extends radially beyond the air inlet end 20 of said air duct and spaced therefrom vertically to permit unobstructed passage of air around said edge into said duct.

The parts B and C heretofore described are permanently assembled with a housing, as D, to form a unit assembly, FIGURES 1 and 3. Said housing is preferably in the form of a plastic, as butyrate, shell of generally hemispherical or dome shape interrupted by a perforated transverse lateral wall portion consisting in part of bars 34 and arranged at one side of and at an angle to the shell axis and at an angle to a relatively flat top wall portion 35. Said lateral wall is provided with perforations in the form of approximately vertical slits 33 separated by said bars 34.

It is contemplated that the aggregate opening area of slits 33 will be less than that of the water discharge ports 25 in frame B, FIGURE 2, so that, when the ventilator ships water, the incoming volume will always be less than the drainage or discharge capacity of said ports 25 and thereby avoid flooding into the entry end 20 of the air duct of frame B. As seen in FIG. 3, the bottom ends of bars 34 are arranged substantially in an arc or obtuse angle arching forwardly so that the bars are in effect disposed in two planes acutely inclined to top wall 35 and at an angle to each other. The arrangement here described provides inclined surfaces for deflecting water away from the slits 33 which afford adequate air passages while said bars 34 effectively intercept and deflect foreign bodies, insects and the like away from said slits.

As seen in FIGURES 3 and 5, the flared skirt portion of housing D is formed with an inwardly exposed annular shoulder 36 which provides a seat adapted to engage the upper edge of outer wall 22 of frame B when housing D

is permanently assembled with said frame. In the form shown, the outer cylindrical surface of outer wall 22 is adhesively or otherwise effectively secured to the opposed annular inner surface of said housing. Thus, the parts B, C and D are securely and permanently fixed in a unit assembly which can be supplied as such along with the initially separate part A.

As seen in the drawings, upper baffle C is permanently secured on frame B with two of its four legs so engaged with ribs 26 that the diametrically opposed laterally arranged legs 30, for example, FIGURE 4, are positioned in water deflecting relation to the relatively short slits 33a at the ends of the series of slits 33. To this extent said two legs supplement the water deflecting function of the main deflector 28 of baffle C.

When mounted on the deck of a boat, for example, the parts above described are assembled as shown in FIG. 3, with the sleeve 10 of base A secured in hole 11 of deck 12; with frame B mounted to rotate freely on base A; with baffle C secured in water-deflecting position on frame B; and with housing D secured to frame B and rotatable therewith to different operating positions. A duct cover E has a flange 37 which fits snugly into the air discharge end 21 of the air duct to close said duct when the ventilator is not in use.

In operation, with the cover E removed from the inner end of the duct, when rain or sea and air drive through slits 33, the water strikes deflector 28 and/or the laterally disposed legs 30 and pours past peripheral edge portions of the deflector 28 toward and through the ports 25, some of it striking peripheral portions of flange 13 of base A and running off to the deck 12 through the annular gap between said flange edge and the flared skirt edge of housing D. Or, when rain or sea drives against the skirt of housing D, part of the water may be deflected by the flared edge portion thereof; and the beveled edge 13a of flange 13 tends to deflect water from the space between said edge and the skirt portion of said housing D.

If conditions so require, housing D along with frame B and baffle C may be rotated freely by hand around their common axis and in relation to base A by reaching through the air duct, gripping finger piece 29 of the baffle and turning the same to such extent and in such direction as may be desired.

45 This application is a continuation-in-part of my pending application Serial No. 17,992, filed March 28, 1960.

I claim:

1. A ventilator adapted to be mounted in operative relation to an opening extending through a deck, or the like, and comprising in combination a base attachable to the deck, and having an opening for co-axial alignment with such deck opening, a frame rotatably mounted for adjustment to different angular positions on said base and having an air duct extending coaxially therethrough and a web portion having angularly spaced arms extending radially from said air duct and providing between them water discharge ports arranged around and outside of said duct, a housing of generally convex dome-like contour mounted on said frame and having a re-entrant portion defined by a substantially flat top wall and a laterally exposed transverse wall joining said top wall at its inner edge and extending upwardly therefrom at an angle thereto and provided with perforations opening therethrough, and a baffle mounted in said housing in operative position between said perforations therein and said air duct and said discharge ports whereby water entering the housing through said perforations is deflected from the inlet end of the air duct by said baffle in a direction to discharge through said ports while air entering through said perforations is permitted to pass the baffle and move into and through the air duct and wherein said base includes a sleeve arranged and adapted to extend through said opening in the deck and a peripheral flange embracing and extending radially from an end portion of said sleeve and provided at its underside with spaced concentric depend-

ing annular ribs coaxial with and spaced from said sleeve and arranged and adapted to receive between them a supply of sealing compound and to retain the same in sealing contact with a deck surface when the base is in operative assembled position thereon, and means for securing the base to a deck or the like with said ribs bearing against said surface.

2. A ventilator according to claim 1, and wherein said sleeve includes bosses extending radially inwardly from an inner surface thereof and arranged and adapted to provide angularly spaced bearings for guiding engagement with portions of the outer surface of said air duct.

3. A ventilator according to claim 1 and wherein an outer edge portion of said peripheral flange of the base is beveled at its underside and the skirt portion of said housing is flared outwardly substantially opposite to and spaced from said beveled edge of said flange whereby water moving across said deck under said skirt periphery is prevented by said beveled flange from entering the housing through the space between said skirt and the beveled edge of said flange.

4. A ventilator according to claim 1 and wherein said frame has a depending annular rib spaced radially from said air duct and which bears on said flange of the base and interengages with said base in overlapping relation to upper end portions of said sleeve thereof to arrest leakage of water between said sleeve and said frame.

5. A ventilator adapted to be mounted in operative relation to an opening extending through a deck, or the like, and comprising in combination a base attachable to the deck, and having an opening for co-axial alignment with such deck opening, a frame rotatably mounted for adjustment to different angular positions on said base and having an air duct extending coaxially therethrough and a web

portion having angularly spaced arms extending radially from said air duct and providing between them water discharge ports arranged around and outside of said duct, a housing of generally convex dome-like contour mounted on said frame and having a re-entrant portion defined by a substantially flat top wall and a laterally exposed transverse wall joining said top wall at its inner edge and extending upwardly therefrom at an angle thereto and provided with perforations opening therethrough, and a baffle mounted in said housing in operative position between said perforations therein and said air duct and said discharge ports whereby water entering the housing through said perforations is deflected from the inlet end of the air duct by said baffle in a direction to discharge through said ports while air entering through said perforations is permitted to pass the baffle and move into and through the air duct and wherein said base includes a sleeve provided at its discharge end with an annular flange extending inwardly and having an exposed oblique face and, said air duct is provided at its discharge end with angularly spaced outwardly extending lugs which are movable across said oblique face of said flange and extend under and slidably engage inner end edge portions of said base.
